UNITED STATES PATENT OFFICE.

JOHN WALKER, OF CLEVELAND, OHIO.

SHAFT-HANGER.

SPECIFICATION forming part of Letters Patent No. 292,879, dated February 5, 1884.

Application filed February 21, 1883. Renewed January 2, 1884. (No model.)

To all whom it may concern:

Be it known that I, JOHN WALKER, of Cleveland, in the county of Cuyahoga and State of Ohio, have invented certain new and useful 5 Improvements in Shaft-Hangers; and I do hereby declare the following to be a full, clear, and exact description of the invention, such as will enable others skilled in the art to which it pertains to make and use the same.

10 My invention relates to improvements in shaft-hangers; and it consists of certain features of construction and combinations of parts, hereinafter described, and pointed out in the claims.

15 In the drawings, Figure 1, is an elevation giving a side view of the frame of the hanger and an end view, one-half of which is in section, of the box, oil-pan, and attachments. Figs. 2 and 3 are detail drawings of portions 20 of Fig. 1. Fig. 4 is an elevation, one-half in perspective, showing an end view of the frame of a hanger and a side view of a box, oil-pan, and portions of a shaft. Fig. 5 is a vertical sectional view of a box, oil-pan, and portions 25 of the hanger, frame, and attachments, and also one view of a scraper or device for scraping the oil from the shaft. Fig. 6 is a plan view of the bottom of an oil-pan, showing also the said scraper. Figs. 7 and 8 are end views, 30 showing the construction of my device.

A represents the frame of the hanger; B, the box, and C the oil-pan nearly surrounding the box. The frame is provided with a vertical cylindrical chamber, a' , above and below the box, and in these chambers are placed the hollow plugs a , with their heads in contact with their respective set-screws a' . The said screws and plugs are for supporting the box and adjusting it vertically. The box may be 35 provided in the center, both above and below, with spherical projections, so placed that they shall have a common radial center, that shall be also the center of the box. The projection on the top of the box engages the open end of 40 the top plug a , while the projection on the bottom of the box rests in a seat in the oil-pan, which in turn has a like projection on the bottom, that engages the open end of the lower plugs a , and thus forms, in effect, a ball-and- 45 socket bearing for the box and oil-pan. The hangers having first been placed in as perfect a line as practicable, it will only be necessary 50

for the box to turn a very short distance to bring itself always in line with the shaft. It will be seen that in this adjustment the open 55 ends of the cups travel over so small a portion of the said spherical projections as to be hardly perceptible. If the parts of the said spherical projections that do not come in contact with the said cups were cut away or had been omitted in making, it is evident that the operations 60 of the device would remain the same. The said remaining portions of the projections, engaging the cups, as aforesaid, would then be in the shape of rings projecting from the box, 65 and it is in this form of projecting rings that I prefer making this part of the device. These 70 ring projections are marked b' , and shown more clearly in Fig. 5. The box is provided with tallow-chambers b , and also with an orifice, b' , in the bottom of the box, through which, by aid of a wick, the oil is drawn from the oil-pan below to lubricate the said box.

The raised seat in the bottom of the oil-pan, as shown in the plan view, Fig. 6, is not a 75 continuous ring like the others aforesaid, but is made of segments of a ring, so placed as to leave spaces c' between the segments for the free passage of oil to this part, as being the lowest portion of the oil-pan, and being also 80 the part from which the oil is drawn by the wick to supply the box above, as aforesaid. The plugs c are for removing oil or sediment 85 from the pan. The oil-pan extends beyond the ends of the box, as shown in Figs. 4 and 5, so as to catch the drip of oil from said box.

Attached to each end of the oil-pan and directly under the shaft, are scrapers (shown more clearly in Figs. 4, 5, 6, 7, and 8) for scraping the oil from the shaft, so that the oil 90 will fall inside of the oil-pan. This device consists of a weighted handle, D, terminating in a bent rod, that passes through a hole in the oil-pan, and is attached to the center of the arm d . This arm is provided at the ends with 95 recesses suitable for attaching scrapers, as shown in the drawings. The attachments of the said rod and the said arm are made by so tight a fit that although the parts can be turned, yet the weighted end of the rod or handle will remain in any position in which it is placed. It will be seen that the handle D may be so placed as to press either end of the arm d and its attached scraper against the 100

shaft. To secure the best result, that end of the arm and its attached scraper should be applied that will come in contact with the shaft when the shaft has a downward motion. This oil returns by its own gravity to the center of the pan, where it is again used for lubricating the box, the sediment remaining at the depressions at the bottom of which are the plugs *c*. It will be seen that the top half or cover 10 of the oil-pan has an annular opening in the center, through which the top plug *a* passes, so that the said plug rests on the box, and not on the cover of the oil-pan. This plug has an oil-hole, *a'*, through which oil may be discharged to a cavity in the center of the box, terminating in an oil-hole leading to the shaft below. The set-screws *a''* are for holding and adjusting laterally the said hollow plugs.

The frame, as shown in Figs. 1 and 2, is 20 made with a cross-sectional opening in one side large enough for passing a shaft in or out of the hanger. This opening is provided with a block, *A'*, that is secured by a bolt passing through the said block, and also through suitable lugs attached to the frame on each side 25 of said opening. The said block and bolt, when in position, support and hold firm these parts of the frame, making them equally strong with the other parts. By removing this block 30 and bolt, the shaft may be taken out of the hanger without removing the pulleys, collars, couplings, or anything, in fact, from the shaft. The block *A'* may be provided with an arm suitable for supporting any desired belt-shifting device. This arm may be made hollow, 35 as shown at *G*, Fig. 2, inclosing an extension-arm, *g*, secured by the set-screw *g'*, by means of which the belt-shifting device may be adjusted to the size of the pulley used.

40 Figs. 9, 10, 11, 12, and 13 illustrate the process by which the frames for these hangers are made.

Fig. 9 represents a pattern for the hanger-frame, with the core-prints *M* attached, ready 45 for making a mold for casting the said frames. The blocks *A'* are first made with a lip, *n*, above and below, as shown in Figs. 12 and 13, and with a hole, as shown by the dotted lines. A core is inserted in the hole and projecting on 50 each side, as shown in Fig. 11, and in this condition it is laid in the mold with the line *x x* of Fig. 11 coincident with the line *x x* of Fig. 9. After placing cores in the prints *M*, the mold is completed and the castings made. 55 After the casting is sufficiently cool, the block *A'* is driven out, leaving that side of the frame as shown in Fig. 10. The lips *n* will have formed recesses in the lugs of the frame, that will serve as guides to the block *A'* when it is 60 desired to place it again in the frame.

It will be seen that the core placed in the block *A'*, as aforesaid, and extending through the lugs on either side will make a straight hole for a bolt without reaming or expending other labor upon it.

65 Blocks with arms, as at *G*, may be substi-

tuted in place of those shown in Figs. 11, 12, and 13, either before or after casting the frame.

While I do not claim, broadly, an adjustable hanger or a self-oiling box, I have no knowledge of the combination of the two in the manner hereinbefore described.

I do not claim in this application the process herein described for casting the frame of the shaft-hanger, but reserve to myself the right to file a separate application for the same.

What I claim is—

1. The combination, with a shaft-hanger 80 having one of its sides divided, of the block secured in the opening thus formed by a bolt, and provided with an extension-arm for supporting the belt-shifting or other device, and capable of being adjusted lengthwise, sub- 85 substantially as shown and described.

2. The combination, with a shaft-hanger having one of its sides divided, of the block secured in the opening thus formed by a bolt, and provided with a hollow outer arm, and 90 the inner arm fitting therein and adapted to be longitudinally adjusted, substantially as and for the purpose described.

3. In a shaft-hanger, the oil-pan having a boss resting on a vertically-adjustable tubular 95 seat below, the oil-box having a ring-like projection on its under side, adapted to rest upon the inner side of said boss, the upper side of the box being provided with a support, and the pan adapted to fit around said support, 100 whereby the box and the pan may adjust themselves to the line of the shaft, substantially as described.

4. The combination, in a shaft-hanger, of 105 the oil-pan, constructed, substantially as described, with the journal-box located within the same, having a ring-like projection adapted to be supported by the pan, and the pan constructed in a cylindrical form, whereby the box is inclosed, substantially as described.

110 5. The combination, in a shaft-hanger, of a cylindrical-like oil-pan, and an inclosed journal-box having a ring-like projection adapted to be supported by the pan, with a scraper constructed to normally bear against 115 the shaft and scrape the oil therefrom, substantially as described.

6. The combination, with the weighted handle *D*, terminating in a bent rod, of the arm *d*, so arranged that either end of the said arm 120 or its attached scraper may be applied to the shaft, substantially as described, and for the purpose set forth.

In testimony whereof I sign this specification, in the presence of two witnesses, this 13th 125 day of February, 1883.

JOHN WALKER.
